UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed August 21, 1922. Serial No. 583,113.

To all whom it may concern:

Be it known that I, WINFRED T. POWELL, a citizen of the United States, residing at Rochester, in the county of Monroe and 5 State of New York, have invented certain new and useful Improvements in Automatic Telephone Systems, of which the following is a full, clear, concise, and exact description.

10 This invention relates to telephone systems and more particularly to telephone systems employing automatic switches in establishing some portion of a telephone connection.

15 One feature of the present invention is the provision of novel means for interconnecting the subscribers of a private automatic exchange and subscribers whose lines terminate at a distant manual office. Another 20 feature of the invention resides in the provision of novel means for controlling a code signaling system. Other features will appear from the detailed description and appended claims.

25 Figs. 1, 2, 3, 4, 5, 6 and 8 when arranged in accordance with the chart of Fig. 9 diagrammatically represent a portion of a telephone system wherein Fig. 1 shows a pair of subscribers' substations and telephone 30 lines leading therefrom to the movable brushes of a rotary line switch. The fixed contacts of the rotary line switch serve as terminals for primary trunks which lead to secondary line switches shown in Fig. 2.

35 The portion of Fig. 2 above and to the right of the dotted line represents a secondary rotary line switch and its operating circuits, herein arbitrarily designated an odd secondary line switch. Below and to the right of 40 the dotted line of Fig. 2 there is represented a rotary line switch herein arbitrarily referred to as an even secondary line switch. In the lower left hand corner of Fig. 3 there is represented a group of relays and their 45 controlling circuits known as the over-flow controlling means for the bridge circuits all of which are common to the private automatic exchange. In the upper portion of Fig. 3 there is represented the equipment 50 associated with a so-called bridge circuit while in the lower right hand corner of this

figure there is represented a so-called sender selector switch which is individual to a bridge circuit and functions to connect its bridge to an idle register sender. In Fig. 55 4 there are represented two rotary stepping switches serving as tens and units registers of a register sender or number storing device. In the lower left hand corner of Fig. 4 there appears a group of multi-contact 60 relays which are common to all the lines of the private automatic exchange, while in the upper left hand corner of this figure there appears a relay with a plurality of contacts, which relay is common to all the lines of a 65 private automatic exchange. Figs. 5 and 6 represent a so-called operator's trunk circuit terminating at one end in the jack of the operator's switchboard or attendant's position and in its other end in the operator's line switch which has access to the terminals of the various bridge circuits. Fig. 7 represents the cord circuit at the 70 operator's position and functions to interconnect the operator's trunk circuit and a 75 trunk circuit (not shown) leading to the main exchange (also omitted). Fig. 8 represents the operating circuits of a so-called code call arrangement, wherein the portion of the circuits above and to the left of the 80 dotted lines represents a code selector for controlling the code signaling, while below and to the left of the dotted line there appears a code line switch which functions to connect a code selector to a calling line over 85 which said selector may be controlled. At the right of the dotted line of Fig. 8 there appears a code connector, the purpose of which is to interconnect the bridge circuit which the calling line has seized and the 90 bridge circuit to which the called line is connected. Fig. 10 is a chart showing the number of impulses to be dialed in order to give the corresponding code signal. Fig. 11 shows the operating circuits of an automatic battery charge device by which the 95 battery of the private automatic exchange is automatically charged from the power circuits of an alternating current source.

The private automatic exchange of this 100 disclosure as shown is arranged to accommodate one hundred lines which terminate

in the movable brushes of fifty line switches. These switches have access to twenty trunks terminating in the movable brushes of twenty secondary line switches which in turn 5 have access to ten bridge circuits. It is also assumed that the five register senders are sufficient to care for the number of simultaneous calls of this system. It will be understood, however, that the number of 10 lines, primary trunks, secondary trunks, bridge circuits and register senders may be greatly varied without departing from the present invention.

The various switches referred to herein 15 may be of the type substantially similar to that disclosed in the patent to Clement #1,707,153 granted August 11, 1914. The multi-contact relays may be of any design of relay in which the armature on actuation 20 closes a plurality of contacts.

It is believed that the invention will best be understood by describing the method of establishing a telephone connection from a substation such as A to a wanted sub- 25 station 24 herein designated B.

It will be noted that the lines leading from substation A and B terminate in the brushes of the same primary line switch but the operation of connecting two telephone lines 30 which do not terminate on the same line switch is not materially different therefrom.

When the subscriber at A initiates a call by removing his receiver from its switch hook a circuit is closed for the line relay 5, 35 extending from grounded battery, winding of this relay, uppermost back contact and armature of cut-off relay 6, over the lower side of the calling line, through the sub- station circuit A in series, over the upper 40 side of the calling line, upper armature and back contact of cut-off relay 7 to ground. In the event that the brushes 8, 9, 10, 11, 12, 13 and 14 of the primary line switch are resting on the terminals of a pair of idle 45 trunk circuits leading to secondary line switches, these trunks will be seized in the manner to be indicated. Let it be assumed, however, that one or both of the first pair of trunks tested by the primary line switch 50 are busy, under which condition the cut-off relay 7 will remain inactive due to the fact that its operating circuit is open at this time so that the motor magnet 15 of the primary line switch has its operating circuit closed 55 from grounded battery, resistance, inner armature and front contact of line relay 5, winding, back contact and armature of the motor magnet 15, lowermost front contact and armature of the line relay 5, inner upper 60 back contact and armature of cut-off relay 6 to ground. Under the control of this circuit the motor magnet advances brushes 8 to 14 of the primary line switch until the test brush 10 encounters the test terminal 65 of an idle trunk, which is characterized by

the presence of ground potential thereon. The cut-off relay 7 is then operated in the circuit from grounded battery resistance, inner armature and front contact of line 70 relay 5, conductor 16, low resistance winding of the cut off relay 6, in series with the low resistance winding of the cut-off relay 7, test brush 10, test conductor 17 of the idle pair of trunks, upper armature and back contact of relay 18 to ground. The circuit 75 just described is effective to shunt the motor magnet 15 to stop the operation of the primary line switch and is also effective to energize the cut off relays 6 and 7. With

these relays energized, the lines extending from substations A and B are connected to idle primary trunk circuits but at this time the extension of the line from substation B to the primary trunk circuit is ineffective 80 since its receiver is on its switch hook. 85

However the operation of the cut-off relay 7 is effective to extend the calling line from substation A through the upper armature and front contact of relay 7, switch brush 8, conductor 19, middle armature and back 90 contact of relay 20 to ground, while the lower side of the calling line is extended through the uppermost armature and front contact of cut-off relay 6, switch brush 9, conductor 21, inner armature and back contact of relay 20, winding of slow releasing 95 relay 22 to grounded battery. Relay 22 is energized in this circuit and immediately closes an operating circuit for the make- 100 busy relay 18, from grounded battery, winding of the relay 18, lowermost front contact and armature of relay 22 to ground. With relay 18 energized a locking circuit for the cut off relays 6 and 7 is completed from 105 grounded battery, resistance, front contact and armature of relay 18, conductor 17, through the high resistance windings of the cut off relays 6 and 7 in multiple, inner front contact and armature of cut-off relay 6 to ground. 110

With relay 22 operated and if the brushes 23, 24, 25, 26 and 27 are not resting in engagement with the terminals of an idle bridge circuit, the motor magnet 28 of the odd secondary line switch advances its brushes over the terminals of such busy bridge circuits. The circuit for effecting the advance of the secondary line switch may be traced as extending from grounded battery, resistance, upper front contact and armature of relay 22, winding of the motor magnet 28, its armature and back contact, inner front contact and armature of relay 22, lower back contact and armature of relay 20 to ground. Idle bridge circuits are indicated by the presence of ground potential 115 on their test terminals such as 29 so that when the test brush of the odd secondary line switch encounters an idle test terminal a circuit is closed from ground, innermost back contact and armature of relay 30, con- 120

ductor 31, test terminal 29, test brush 23, inner back contact and armature of relay 32, upper winding of relay 20, upper armature and front contact of relay 22, resistance 5 to grounded battery. This circuit is effective to short circuit the motor magnet 28 and also to effect the energization of the relay 20. This last relay at its front contact and armature extends the calling line to 10 the brushes 26 and 27 of the secondary line switch whereupon an energizing circuit is closed for the relay 33 from grounded battery, right hand winding of this relay, left hand back contact and armature of relay 15 35, outer back contact and continuity spring of relay 34, conductor 36, through the line switch brush 27 to which the lower side of the calling line has already been extended, and over the upper side of the calling line 20 of the extended connection to test brush 26, conductor 37 inner continuity spring and back contact of relay 34, left hand winding of relay 33 to ground. The relay 33 is energized in this circuit and at its armature 25 and front contact effects the operation of the slow releasing relay 30. This relay at its innermost back contact and armature disconnects the idle ground potential from test terminal 29 and completes a holding circuit 30 for the relay 20 from grounded battery, resistance innermost front contact and armature of relay 30, conductor 31, left hand winding of relay 32, lower winding, front contact and armature of relay 20 to ground. 35 It will be noted that although the holding circuit for the make-busy relay 18 is opened by the deenergization of relay 22, a substitute holding circuit for this relay is now closed at the lowermost front contact and 40 armature of relay 20 to ground. The idle sender selectors of which there is one for each bridge circuit are normally standing in such position that their brushes are in engagement with contacts of idle register 45 senders. However, as soon as the bridge circuit of Fig. 3 is selected, the relay 35 is operated in a circuit traceable from grounded battery, winding, back contact and armature of the motor magnet 38, winding 50 of relay 35, inner armature and back contact of relay 39, back contact and continuity spring of the trip relay 40, right hand back contact and armature or ringing relay 41, contact 42 and armature of relay 30 to ground. 55 When relay 35 is thus operated, ground is applied at its innermost armature and front contact, selector test brush 42 and through the multiple test terminals associated with the register sender Fig. 4. 60 Therefore each sender selector whose test brush similar to 42 is standing in engagement with a multiple terminal of 42 has an operating circuit closed from grounded battery through a motor magnet similar to 38, its back contact and armature, an armature 65 and contact similar to 44 of a relay like 35, through a test brush similar to 42 and a multiple test terminal 43 to ground over the path just described therefore, all sender selectors will advance their brushes until 70 the test brushes no longer encounter ground potential.

Also with relay 35 operated the conductor 36 of the bridge circuit which has been connected to the calling line is extended 75 through the left hand armature and front contact of relay 35, sender selector brush 45, conductor 46, winding of the impulse relay 47, secondary winding of the induction coil to grounded battery 80

As soon as this circuit is completed, a source of dial tone is extended to the calling line to inform the calling party that a register sender has been seized and that the apparatus is in condition to receive directive impulses corresponding to the designation of the wanted subscriber's line. 85

The calling subscriber now proceeds to send impulses corresponding to the tens digit of the wanted number. It is assumed 90 that this wanted number is "24," the calling subscriber than transmits two impulses in response to each of which the impulse relay 47 retracts its armatures. On the first attraction of the armature of the relay 47, a 95 circuit is closed from ground, left hand armature and front contact of this relay, conductor 48, tens register brush 49 in its first position, back contact armature and winding of the motor magnet 50 to grounded battery. This circuit is effective to advance the tens register into its second position when the change-over relay 52 is energized in series with relay 62 through off-normal contacts 57. When the impulse relay 47 100 deenergizes in reponse to the first tens impulse an operating circuit is extended from grounded battery, winding, back contact and armature of motor magnet 50, brush 49 in its second position, conductor 51, back 105 contact and armature of relay 47 to ground. Under the control of this circuit the tens register is moved to position 3. At the close of this impulse, relay 47 is energized and advances the tens register into position 110 4, over a circuit closed from grounded battery, winding, back contact and armature of motor magnet 50, brush 49 in its third position, inner front contact and armature of relay 52, conductor 53, right hand front 115 contact and armature of relay 47, conductor 59, off-normal contacts 60 to ground. 120

In response to the last tens impulse relay 47 retracts its armature to close a circuit for advancing the tens register into its fifth position. This circuit may be described as extending from grounded battery, winding, back contact and armature of motor magnet 50, brush 49 in its fourth position, outer armature and front contact of change-over 125 130

4 relay 52, conductor 58, right hand back contact and armature of impulse relay 47, conductor 59, off normal contacts 60 to ground. It will be noted that after the tens register 5 reaches position 3, an energizing circuit for the change-over relay 52 is extended from grounded battery, winding of relay 62, conductor 63, winding of relay 52, off normal contacts 64, through register brush 49, to 10 ground in multiple with the operating circuit just described for the motor magnet 50. At the close of this second impulse the relay 47 is again energized and the motor magnet 50 is now operated to advance the tens 15 register into its sixth position. This operating circuit is closed from grounded battery, winding, back contact and armature of the motor magnet 50, brush 49 in its fifth position, inner front contact and armature 20 of change-over relay 52, conductor 53, right hand front contact and armature of relay 47, conductor 59, off normal contacts 60 to ground.

At the close of the tens series of impulses 25 the impulse relay 47 holds its armatures attracted for a relatively long period, so that the operating circuit for relay 52 is interrupted, permitting this relay to retract its armatures. As soon as this takes place the 30 units register is advanced into position two by a circuit closed for its motor magnet from grounded battery, winding, armature and back contact of motor magnet 65, units register brush 66 in its first position, conductor 67, inner back contact and armature 35 of change-over relay 52, conductor 53, right hand front contact and armature of relay 47, conductor 59, off normal contacts 60 to ground. The units register is now in condition 40 to receive the units series of impulses, and in response to the first of these impulses the relay 47 retracts its armatures to close a circuit from ground, its left hand armature and back contact, conductor 51, units 45 register brush 66 in its second position, back contact, armature and winding of the motor magnet 65 to grounded battery. Under the control of this circuit the units register brushes are advanced into 50 their third position. It should be noted that the energizing circuit for the change-over relay 68 of the units register is closed in multiple with the operating circuit of the motor magnet 65. When the relay 47 55 retracts its armatures at the close of the first units impulses, the motor magnet is again operated over its initial operating circuit including conductors 67, 53 and 59 to advance the units register into its fourth position. When the impulse relay 47 again 60 deenergizes and energizes in response to the second impulse of such series, the units register is advanced through position 5 into position 6 and in response to the third and 65 fourth impulse of this series the units reg-

ister is advanced through positions 7, 8 and 9 into position 10. It should be stated that relay 106 is energized during dialing, over brush 103 and conductor 102 to ground at changeover relays 52 and 68. With relay 70 70 actuated, relay 30 is held operated and the left hand winding of relay 33 is short circuited to remove the impedance of this relay during impulsion.

At the close of this series of impulses 75 when the units change-over relay 68 deenergizes, multi-contact test relay 70 is actuated from grounded battery, winding of the relay 70, units register brush 71 in its tenth position, conductor 72, armature and back contact of change-over relay 68 through both windings in series of relay 73, lowermost continuity spring and back contact of this relay, innermost back contacts and continuity springs of relays 74 and 75 at the 80 other register senders provided, to ground at the inner back contact, continuity spring of relay 73. This last described circuit is for the purpose of permitting the testing of only one calling line at a time. In the 85 event that some other sender is testing a called line its relay such as 74 or 75 is operated to prevent the completion of the circuit just described. As soon as relay 73 is 90 operated it closes a locking circuit for itself 95 through its inner lower armature and continuity spring, while at its uppermost back contact and armature it opens the energizing circuit of the relay 76. This relay is slow in releasing but before it retracts its 100 armature the test circuit of the called line is closed from ground at the lower armature and front contact of relay 77, right hand armature, front contact and winding of relay 76, tens register brush 78, contact 79 of 105 multi-contact test relay 70, conductor 80, inner armature and front contact of cutoff relay 7, primary line switch brush 11, conductor 81, uppermost armature and contact of relay 82, left hand winding of relay 83, conductor 84, uppermost back contact and armature of relay 85 to grounded battery. It will be understood that the relay 85 is 110 not operated at this time due to the fact that its operating circuit is opened at the 115 units register brush 86, since the units register has not been advanced into an odd position. The relay 83 of Fig. 2 is operated in the circuit just described for a purpose 120 which will be pointed out.

At this point it may be well to explain that if the primary line switch of the called line is not already extended to a primary trunk circuit the test conductor such as 80 will be extended through the inner armature and back contact of cut-off relay 7, 125 winding of line relay 5 to grounded battery. The line relay 5 is thus energized and causes the motor magnet 15 to advance the primary line switch brushes into engage- 130

ment with a pair of idle primary trunks whereupon the test conductor 80 will then be extended to conductor 81 associated with one of the selected primary trunks to complete the test circuit as already described.

It has been pointed out that the relay 83 of Fig. 2 is energized in the test circuit and attracts its armatures to render the terminating test brush 86 effective instead of the originating test brush 87. Also with the relay 83 energized the relay 88 is operated in a circuit closed from grounded battery, winding of relay 88, front contact and armature of relay 83, inner upper back contact and armature of relay 82 to ground. The operation of relay 88 closes an actuating circuit for the motor magnet 90 of the even secondary line switch, which is traced from grounded battery, resistance, lower contact and armature of relay 88, winding armature and back contact of motor magnet 90, front contact and upper armature of relay 88, back contact and armature of relay 82 to ground. Under the control of this circuit the motor magnet 90 advances its brushes 86, 87, 91, 92, and 93 until its test brush 86 reaches the bridge circuit to which the calling line has already been extended. At this time the motor magnet 90 is shunted and the relay 82 operates in a circuit from grounded battery, resistance, lower front contact and armature of relay 88, lower winding of relay 82, inner armature and front contact of relay 83, test brush 86, test terminal 94, test conductor 95, sender selector brush 96, conductor 97, front contact and upper armature of relay 77 to ground. Relay 82 when thus operated closes a locking circuit for itself from ground through its upper armature front contact and winding, right hand winding of relay 83 brush 87, terminal 98, conductor 99, outer armature and front contact of relay 80, continuity spring and back contact of trip relay 40, winding of ringing relay 41 to grounded battery. Relay 82 is thus locked operated and the ringing relay 41 attracts its armatures to apply ringing current from the source of ringing current through the right hand winding of the trip relay 40, front contact and armature of the ringing relay 41, over the selected primary trunk and the called line in series, right hand front contact and armature of ringing relay 41, contact 42 and armature of relay 30 to ground. Ringing current is applied over this circuit to the called line until the subscriber thereon removes his receiver from its switch hook, at which time trip relay 40 receives sufficient current to energize and attract its armatures. At the right hand armature and continuity spring of relay 40 grounded battery is applied through the resistance, outermost front contact and armature of relay 30 to the holding conductor 99 which maintains the relay 82 operated dur-

ing this connection. At the right hand back contact and continuity spring, the energizing circuit of the ringing relay 41 is interrupted causing this relay to deenergize, which operation closes a locking circuit for the trip relay 40 from grounded battery, its winding, lefthand armature and continuity spring, right hand back contact and armature of ringing relay 41, contact 42 and armature of relay 30 to ground. The de-energization of the ringing relay 41 also closes a break-point in the called end of the connection so that talking current is supplied to the called subscriber through both windings in series of the relay 34. This energizes the relay 34 and opens the impulsing circuit, which has previously been extended to the register sender of Fig. 4.

As soon as the ringing relay 41 attracts its armatures the holding circuit of the relay 35 is opened causing this relay to deenergize, whereupon, the holding circuit for the holding relay 55 is broken which was completed over conductor 100, brush 42, armature and front contact of relay 35 to ground. The holding relay 55 then deenergizes to effect the restoration of the register sender to its normal position. This is accomplished in the following manner. The tens register is restored in a circuit closed from grounded battery winding of its motor magnet 50, back contact and armature thereof, off normal contacts 64 which are closed in positions 3 to 25 inclusive, conductor 56, middle contact and armature of relay 55, conductors 54 and 59, off normal contacts 60 to ground. The relay 62 is held operated in multiple with the operating circuit of the motor magnet 50, in order to render the register sender unselectable until its registers have been restored to normal position. This circuit extends from grounded battery, winding of relay 62, conductor 63, winding of relay 52 to ground as described over conductor 56. The last described circuit of the motor magnet 50 is effective to advance the tens register into its first or normal position. The restoring circuit of the units register extends from grounded battery, winding, armature and back contact of magnet 65, off-normal contacts 101, inner back contact and armature of relay 55 to ground. The relay 62 is energized in multiple with the operating circuit of the units register magnet and at its armature and front contact applies ground to conductor 100 to render this register sender unselectable until its registers are restored to normal.

At the close of the conversation when the calling party replaces his receiver on its switch hook, the battery feed relay 33 de-energizes and shortly afterwards the slow releasing relay 30 retracts its armatures to open the holding conductor 31. This causes the deenergization of the holding relay 20

which releases the odd secondary line switch and also opens one branch of the circuit of the relay 18. The release of the relay 30 also interrupts the holding conductor 99 which was maintaining the even secondary line switch operated. The opening of this circuit causes relay 82 to deenergize to effect the release of the secondary line switch. Also the release of relay 82 opens the other branch of the holding circuit of relay 18 which deenergizes to effect the deenergization of relays 6 and 7 which cause the release of the primary line switch.

Call to busy line.

Let it be assumed that the wanted line is busy at the time that the test thereof is made. Under this condition which is indicated by the energization of relay 82 of the even secondary line switch the test conductor 81 is not completed so that relay 76 of the register sender of Fig. 4 is not maintained operated. When slow releasing relay 76 deenergizes, an operating circuit is closed for the busy test relay 39 of Fig. 3 from grounded battery, winding of this relay, its continuity spring and back contact, middle armature and front contact of relay 35, selector brush 152, conductor 104, back contact and armature of relay 76, lower front contact and armature of relay 77 to ground. Relay 39 is energized in this circuit and is then locked operated through its continuity spring to ground at contact 42 and armature of relay 30. A source of busy tone current BZ is then applied to the calling line through the upper armature and front contact of relay 39 and conductor 105. The calling subscriber on hearing this busy tone knows that the wanted line cannot be reached and replaces his receiver on its switch hook to restore the connection until some later time. The energization of relay 39 opens the holding circuit of relay 35 which deenergizes to effect the release of the register sender of Fig. 4, as already described.

Automatic call to main office.

Let it be assumed that the subscriber at A desires to call a subscriber located at the main office, it then becomes necessary for the subscriber at A to signal the private branch exchange operator, this is accomplished by dialing "00". When the subscriber initiates such a call, the calling line is extended through his primary line switch and an idle secondary line switch to a bridge circuit and thence through the sender selector to an idle register sender in the manner already indicated in the case of a full automatic call. On hearing the dial tone the subscriber first dials "0" to advance the tens register into position 22 and then dials "0" a second time to set the units register into position 22, all of which takes place

in the manner already described. It will, of course, be understood that the setting of the units register completes an energizing circuit for the relays 108 and 145 of the group of multi-contact relays so that the test circuit to the operator's position is extended from ground at the armature and front contact of relay 77, armature front contact and winding of relay 76, brush 78, conductor 109, contact 110, armature and contact 111, conductor 112 which conductor is continued to the upper left hand corner of Fig. 6, left hand armature and back contact of relay 113, conductor 114, winding of slow releasing relay 115 to grounded battery. Relay 115 is energized in this circuit and at its right hand armature and front contact causes the operation of relay 116. This last named relay when energized, closes an operating circuit for the motor magnet 117 of the operator's line switch. This circuit may be described as extending from grounded battery, resistance, left hand front contact and armature of relay 116, winding armature and back contact of motor magnet 117, right hand front contact and armature of relay 116, upper back contact and armature of relay 118 to ground. Under the control of this circuit, the motor magnet 117 advances its brushes 119, 120, 121, 122 and 123 over the contacts of various bridge circuits until the bridge circuit to which the calling line has been extended, is reached. At this time relay 118 is operated from grounded battery, resistance, left hand front contact and armature of relay 116, lower winding of relay 118, inner armature and front contact of relay 115, brush 120, test contact 124, conductor 95, sender selector brush 96, conductor 97, upper front contact and armature of relay 77 to ground. This circuit is also effective to shunt the motor magnet 117 to stop the operator's line switch with its brushes in engagement with the bridge circuit now connected to the calling line. The relay 118 is thus energized and closes a locking circuit for itself through its inner upper armature, front contact and winding, line switch brush 119, terminal 125, conductor 99, outermost armature and front contact of relay 30, right hand continuity spring and back contact of trip relay 40, winding of ringing relay 41 to grounded battery.

The ringing relay is also energized at this time and closes the ringing circuit including the right hand winding of the trip relay 40, left hand front contact and armature of the ringing relay, over the lower side of the bridge circuit, operator's line switch brush 122 of Fig. 6, inner lower front contact and armature of relay 118, right hand continuity spring and back contact of relay 126, lowermost armature and back contact of relay 127, right hand winding of relay 128, 130

through the source of current, left hand winding of this relay, inner back contact and armature of relay 127, left hand back contact and continuity spring of relay 126, 5 lowermost armature and front contact of relay 118, line switch brush 123, upper side of the bridge circuit, resistance, right hand front contact and armature of the ringing relay 41, contact 42 and armature of relay 10 30 to ground. This last described circuit is effective to trip the ringing at the bridge circuit whereupon the ringing relay 41 de-energizes and the relay 128 of Fig. 5 is then energized in series with both circuits of relay 15 34. As soon as the relay 128 is operated it closes an energizing circuit for the relay 129, extending from grounded battery, winding of this relay, jack contacts 130, conductor 131, winding of relay 132, armature and 20 front contact of relay 128, conductor 133, jack contacts 134 and 135 to ground.

If the calling subscriber is entitled to a connection with the main office his line switch is connected with a brush such as 12 25 of Fig. 1 which connects ground potential at the upper armature and front contact of the cut off relay 6, over conductor 137, armature and front contact of relay 32, conductor 138, secondary line switch brush 25, conductor 139, terminal 140, thence the circuit is completed through operator's line switch brush 121, uppermost armature and front contact of relay 118, conductor 141, winding of relay 142 to grounded battery. Lamp 30 143, is then operated in a circuit completed through front contacts and armatures of relay 142 and 129. It will be understood that the signals 143 and 144 may be of different character such as different colors or different locations so that on noting this signal the operator will know whether or not the subscriber calling from the private automatic exchange is entitled to the connection with the main office.

45 The operator on noting that the lamp 143 is lighted, knows that this calling subscriber is entitled to service through the main exchange and she therefore inserts the answering plug P of the cord circuit of Fig. 7 into the jack J of the trunk circuit of Fig. 5. Since ground potential is applied over the sleeve of the jack J, a break point is closed in the operating circuit of the answering supervisory lamp 198. This lamp is not 50 lighted, however, at this time since the supervisory relay 199 is energized from grounded battery, left hand winding of this relay, lower side of the cord circuit, ring contacts of the plug conductor 131, impedance coil 132, armature and front contact of the relay 138, conductor 133, right hand armature and front contact of relay 142, tip contacts of plug and jack, right hand winding of relay 199 to ground.

55 60 65 After inserting the answering plug into

the jack of the calling trunk the operator throws her listening key L. K. to ascertain the number of the wanted subscriber, whereupon she inserts the plug P' into the jack of a trunk leading to the main office (not 70 shown). The jack J of this disclosure is constructed to cooperate with a plug of such design that the tip contact of the plug opens tip contacts in the trunk conductors leading to the calling line so that if relay 142 75 is not operated it will be impossible for the calling subscriber who is not entitled to a connection with the main exchange to talk through the connection so extended. Such an arrangement is provided to make the discrimination between subscribers entitled to 80 a connection at the main exchange and those not entitled to such a connection, independent of operator's control. It will, of course, be sufficient to signal the operator by means 85 of lamps 143 and 144 and instruct her not to extend such originating calls as light the lamp 144. In this event the automatic discriminating means may be omitted and standard plugs and jacks employed. In this 90 instance also talking battery is supplied to the calling and called sides of the bridge circuit through the windings of relays 33 and 34. At the conclusion of the connection when the subscriber at A replaces his receiver on its switch hook, relay 33 deenergizes in the manner previously described to effect the release of relay 30. This last mentioned relay at its outer armature and front 95 contact opens the holding conductor 99 100 which has been maintaining relay 118 of the operator's line switch energized. Relay 118 thereupon deenergizes and releases the operator's line switch for use on a succeeding 105 call. The release of relay 118 also effects the deenergization of relay 128, which relay effects the release of supervisory relay 199 and lamp 198 is lighted to indicate to the operator that it is time for disconnection. The operator then removes the calling plug from 110 the jack of the trunk to the distant office and the answering plug P of the cord circuit which she has used, from the jack J to restore the connection.

115 *Call from main exchange to the private automatic exchange.*

Let it be assumed that the subscriber whose line terminates at the main exchange (not shown) has originated a call to a subscriber's line terminating at the private automatic exchange. The operator at the distant office thereupon extends the calling line through the main office and through a trunk circuit to the attendant operator's position 120 associated with the private automatic exchange. The extension of a call to this position lights a lamp (not shown) associated with the jack of the trunk from the distant office. The attendant operator on noting 125 130

the lighting of this lamp inserts the plug P into the jack of the operator's trunk (Fig. 5) and after throwing the listening key L. K. to connect her head set to this trunk she 5 ascertains the number of the wanted line. The attendant operator now inserts the plug P' into the jack J which serves as a terminal of the operator's trunk connected to the private automatic exchange. This closes 10 jack contacts 201 by which a circuit is closed from grounded battery, winding of relay 127, right hand back contact and armature of relay 113, jack contacts 201 to ground. Relay 127 on energization closes a locking 15 circuit for itself, through its inner upper front contact and armature, which circuit is independent of the armature and back contact of the relay 113. This locking circuit also includes the upper winding of the 20 polarized relay 202 in multiple. Relay 202 is not operated, however, until the called party answers which reverses battery over the trunk by the operation of the relay 34. Relay 127 disconnects the relay 128 which 25 relay is used when this trunk functions to extend a call from a private automatic subscriber to a subscriber at the main exchange. Relay 127 at this time also closes a bridge across its trunk to the operator's line switch 30 30 which bridge includes the lower winding of the relay 202 and the impedance coil 203. The relay 116 of Fig. 6 is also energized in series with the relay 202 and coil 203 and when thus operated closes an operating 35 circuit for the motor magnet 117 by which the brushes 119 to 123 inclusive of the operator's line switch are advanced to seize the originating terminals of an idle bridge circuit.

40 When such an idle bridge circuit is located the relay 118 is operated in the manner already described to disable the relay 116 and to close break points in the operator's trunk circuit. At this time a circuit is closed 45 from ground at the innermost upper armature and front contact of relay 118, conductor 205, left hand winding of relay 113 to grounded battery. This relay serves to extend the operator's test circuit 112 through 50 the left hand armature and front contact of relay 113 conductor 206, outermost armature and back contact of relay 115 to the next idle trunk switch to render said trunk switch selectable on a succeeding call.

55 Since the operator's line switch which has thus seized the bridge circuit is resting on an originating set of terminals, line switch brush 121 is connected to ground which operates the relay 142 to bridge a break 60 point in the tip conductor of the operator's trunk opened by the large tip of the operator's cord circuit plug. The operator now depresses the common dial key 207 which energizes the relay 126 to connect the 65 dial 208 across the operator's trunk.

The wanted number is now dialed and the fast relay 209 and the slow releasing relay 126 are held operated during each rotation of the dial. Impulses from the dial 208 are transmitted over the operator's trunk and 70 through the selected bridge circuit to a register sender similar to that shown in Fig. 4, whereupon the testing of the called line is effected, and if idle, primary and secondary line switches extend this line to the terminating end of the bridge circuit to which the operator's trunk is connected. Thereafter the ringing, talking and releasing operations are effected in the manner already 75 described. 80

If the dial key 207 is restored before the dial completes its operation for the last digit, ground at the back contact of the dial key is extended through the front contact of the fast operating relay 209, through 85 the front contact and armature of relay 127, armature and back contact of relay 210, winding of relay 126 to grounded battery which maintains the relay 126 energized. When, however, the dial completes its operation and the dial key is restored, ground at the back contact of the dial key is extended through the armature and back contact of relay 209, inner armature and front contact of relay 126, winding of relay 210 90 to grounded battery. 95

Relay 210 is operated in this circuit and closes a locking circuit for itself through its lower front contact and armature as long as the operator's cord circuit is in the jack J. 100 The energization of relay 210 effects the release of relay 126, which disconnects the dial 208 from this trunk as long as the plug is in the jack J.

The response of the called party actuates 105 the relay 34 of Fig. 3 which reverses the direction of battery supplied over the terminating end of the bridge circuit and thereby effects the operation of the polarized relay 202 which last named relay provides 110 supervision on the operator's cord circuit. 115

Code call.

In the present system provisions are made 115 for locating executives of the plant who happen to be away from their desks at the time when they are wanted. Such an arrangement is known as a code call and consists of signals such as lamps or gongs located at various parts of the office or factory and of suitable actuating mechanism by which the lamps or gongs may be operated according to a predetermined code of long and short impulses, one code being assigned 120 to each of the persons to be called. 125

Let it be assumed that the subscriber at A desires to locate a person who may be reached by the code call, the subscriber first removes his receiver from its switch hook to extend his line through primary. 130

and secondary line switches to a bridge and thence through a sender selector to an idle register sender all of which takes place as in the case of an ordinary call in the 5 manner already described. In order to be able to send out the code call the subscriber is instructed to dial "09" which is effective to actuate the multi-contact relay 145 of the group of multi-contact relays so that a test 10 circuit is then extended to register brush 78, conductor 109, contact and armature 110 of relay 145, contact and armature 146 of relay 108, conductor 147, lowermost armature and back contact of relay 148, Fig. 15 8, winding of slow releasing relay 149, selector brush 150 in its first position, outer armature and back contact of relay 151, resistance 152 to grounded battery. The relay 149 is thus operated and closes an 20 actuating circuit for the motor magnet 153 of the code line switch by which its brushes 154, 155, 156 and 157 are advanced to locate the bridge circuit to which the calling line has been connected. The circuit of 25 the motor magnet 153 is closed from ground at the inner armature and back contact of relay 148, inner armature and front contact of relay 149, back contact, armature and winding of the motor magnet 153, uppermost front contact and armature of relay 149, resistance 152 to grounded battery. When the calling bridge circuit is located, the motor magnet 153 is shunted and the 30 relay 148 is operated in a circuit completed from grounded battery, resistance 152, uppermost armature and front contact of relay 149, upper winding of relay 148 conductor 158, code line switch brush 157, conductor 159, conductor 95, sender selector brush 35 96, conductor 97, front contact and upper armature of relay 77 to ground. The relay 148 when operated closes a locking circuit for itself from ground its lower armature, front contact and lower winding, conductor 40 160, line switch brush 154, conductor 99, outer armature and front contact of relay 30, continuity spring and back contact of relay 40, winding of ringing relay 41 to 45 grounded battery.

50 As soon as the relay 148 is energized it opens the energizing circuit of relay 149 causing it to release. The operation of relay 148 also connects the left hand winding of the impulse relay 161 in multiple 55 with the calling line, and this relay operates in parallel with relay 33 of the bridge circuit which has been connected to the calling line. A circuit is now closed from ground at the inner lower armature and front contact of relay 148, conductor 162, code-selector brush 163, back contact and armature of motor magnet 164, armature and front contact of relay 161, code selector brush 165 in its first position, back 60 contact and middle armature of relay 166,

winding of the motor magnet 164 to grounded battery. Under the control of this circuit the code selector is advanced to position 2 as soon as the code selector has been connected to the calling line, the calling subscriber then proceeds to dial the number of impulses corresponding to the codes assigned to the wanted party. 70

In response to each of the impulses corresponding to the code number, an impulse circuit is closed from ground at the armature and front contact of relay 148, conductor 162, brush 163, left hand armature and back contact of impulse relay 161, brush 165, back contact and middle armature of relay 166, winding of the motor magnet 164 to grounded battery. If six impulses are transmitted for the first digit, the switching relays 167 or 168 will not operate due to the fact that the motor magnet 164 advances code selector brush 150 past the contacts to which energizing circuits of these relays are connected. However, if No. 5 is the first digit the motor magnet 164 advances the code selector brushes into such 80 position that brush 150 completes an operating circuit for the switching relay 167 as soon as the change-over relay 151 deenergizes. This circuit extends from ground, left hand winding of relay 167, brush 150 85 in its seventh position, outer armature and back contact of relay 151, resistance 152, to grounded battery. 90

Relay 167 when thus energized closes a locking circuit for itself from ground, 100 through its left hand winding, front contact and armature, brush 169, conductor 170, resistance 152 to grounded battery. When No. 4 is dialed for the first digit, the brush 150 is advanced into its sixth position 105 whereupon relay 168 is operated through its left hand winding and thereupon closes a locking circuit for itself through brush 169 in the manner already indicated. However, if No. 3 is the first digit dialed, 110 the brush 150 is advanced into its fifth position where operating circuits are closed for the relays 167 and 168.

In response to the next series of impulses the motor magnet 164 is operated in the manner already described to advance the brushes of the code selector a desired number of steps. By reference to the table shown in Fig. 10 it will be noted that the code selector has twenty-five different positions and with two switching relays such as 115 167 and 168 it is possible to obtain 12 different codes by dialing two series of code impulses. The small "x" appearing in this table indicates the position of the code selector brushes just prior to the time when they begin their advance to actuate a code alarm. 120

As soon as the two series of code impulses 125 have been received by the code selector the

change-over relay 151 again deenergizes. At this time, however, the brush 163 of the code selector has been advanced past its eighth position, so that the switching relay 166 is now operated in a circuit closed from grounded battery, through its lower winding, back contact and armature of relay 151, selector brush 163 in some one of the positions 9 to 25 inclusive, conductor 162, lower front contact and armature of relay 148 to ground. The relay 166 in turn closes a locking circuit for itself from ground through its upper winding, front contact and armature, selector brush 169, conductor 170, resistance 152 to grounded battery. Also with the switching relay 166 operated, a circuit is closed from ground at the interrupter (not shown) conductor 171, lowermost front contact and armature of relay 166, winding 20 of the motor magnet 164 to grounded battery.

Under the control of this circuit the motor magnet 164 advances the brushes of the code selector and while the brush 150 is passing through its position 9 to 25 various long and short ringing signals are produced by the gongs such as 172, depending on the original position of the brush 150 and also depending upon which of the switching relays 167 or 168 is operated. Under the control of the mentioned circuit, the motor magnet 164 advances the brushes of the code selector into their normal position whereupon relays 166, 167 and 168 are released but the code selector takes a preliminary step into its first position so that the calling party can again dial the code number to repeat the code ringing without the necessity of releasing the connection and again dialing 40 "#09" to select the code circuit.

It will be noted that the code selector brush 150 disconnects battery from relay 149 in all its positions except position one, this is to prevent the switch from being seized until it is in its normal position. It will also be seen that when the relay 166 operates, the wanted code signal is produced in full, even though the calling party releases during the time that the gong 172 is being actuated.

When the wanted party hears his code signal he proceeds to the nearest telephone and dials "No. 09" this is accomplished in the following manner. On removing the receiver from its switch hook, the primary line switch of the answering line seizes a secondary line switch which in turn extends the calling line through an idle bridge circuit and a sender selector to an idle register sender. This register sender is adjusted in response to the #09 to extend the test conductor 147 through the lowermost armature and front contact of relay 148, armature and back contact of relay 149, winding of slow releasing relay 173, conductor 174, upper-

most back contact and armature of relay 175, conductor 176, resistance 152 to grounded battery.

Relay 173 is operated in this circuit and closes an actuating circuit for the motor magnet 177 which advances the brushes 178, 179, 180 and 181 of the code connector to connect the answering line and the bridge circuit to which it is connected to the calling line and to the bridge to which it is connected. When this connection is completed relay 175 is operated from grounded battery, resistance 182, inner armature and front contact of relay 173, lower winding of relay 175, code connector brush 181, conductor 183, a conductor similar to 95 of the bridge circuit to which the answering line is connected, brush 96, conductor 97 and upper contact of relay 77 to ground; all of which circuits are associated with the sender selector and register sender to which the answering line is connected.

When relay 175 operates it interrupts the energizing circuit of relay 173 which deenergizes. It will be seen that the called and calling lines are now connected in multiple through condensers of the code connector. The test circuit "09" of the code signaling tests busy until both the calling and answering parties release the connection.

The ringing is not tripped on the bridges used in this connection, but this operation is not necessary because there is no line circuit on the terminating end of either bridge circuit.

Overflow circuits.

It will be noted by reference to Figs. 1 and 2 that overflow circuits are provided. This is for the purpose of preventing primary and secondary line switches from rotating continuously when all the primary trunks and all of the bridge circuits are in use. The operation of the primary overflow circuit is as follows. As long as any primary trunks are idle, the relay 187 is inert due to the fact that it is short-circuited by ground at the lower armature and back contact of some one of the relays 18 associated with a primary trunk circuit. For this reason the stopping condition is not present on the over-flow terminals. When, however, all the primary trunks are engaged all of the relays similar to 18 are operated and the relay 187 is then actuated in a circuit closed from ground, winding of this relay, armature and front contact of relay 18, conductor 188, resistance to grounded battery. At the lower armature and front contact of relay 187 ground is applied to the terminal 189 of the overflow trunk so that when the brush 10 of the primary line switch of the calling line encounters this terminal, the primary line switch is stopped.

as has been described and the calling line is extended through brushes 8 and 9, through both windings of relay 190 in series to ground and grounded battery respectively. Relay 190 is thus energized and effects the operation of relay 191. With the relays 187 and 191 thus energized, holding battery is extended through the front contacts and armatures of these relays, over conductor 192, test terminal 189, test brush 10, through the high resistance windings of relays 7 and 6, upper front contact and armature of relay 6 to ground.

The calling subscriber's line is thus held in engagement with the over-flow trunk as long as the calling subscriber continues to keep his receiver from its switch hook and a busy tone is applied from the source of busy tone current BZ and upper winding of relay 190 to the calling line.

Similarly while any of the bridge circuits of Fig. 3 are idle, relay 193 is short-circuited by ground at the armature 194 of relay 30. When, however, all the bridge circuits are in use all relays similar to 30 are operated so that the relay 193 is then energized in a circuit closed from ground, lower winding of this relay, armature 194 and front contact of relay 30, lefthand winding of relay 185 to grounded battery. With the relay 193 thus operated stopping potential is applied to test terminal 195 of the over-flow bridge which causes the secondary line switch to stop on the over-flow bridge circuit and thereby effects the operation of relay 196. This actuates the slow releasing relay 197 and holding battery potential is applied through resistance 198, and through the armatures and front contacts of the relays 193 and 197 to the test terminal 195.

Battery charging arrangement.

In Fig. 11 there is shown an arrangement for charging the direct current battery of the private automatic exchange from a source of alternating current. In this arrangement any well known current rectifying device such as is indicated at 250 may be employed for rectifying the source of alternating current to charge the battery 251. In addition a voltmeter relay of well known construction is employed and functions when the voltage of the battery 251 becomes too low, to close contacts 252, and when the voltage of the battery 251 has reached a predetermined maximum amount, contacts 253 are closed as will be described.

The relay 254 herein shown is provided with two windings and is known as a carbon contact relay because its contacts are of carbon to prevent serious arcing when the power circuits are opened.

In the operation of this arrangement, when the contacts 252 of the voltmeter relay are closed due to the fact that the volt-

age of battery 251 has reached a predetermined minimum amount, a circuit is closed from ground, contacts 252, winding of relay 255 to grounded battery. Relay 255 is thus energized and closes a locking circuit for itself from grounded battery, its winding, conductor 256, lower back contact and armature of relay 257, lower armature and front contact of relay 255 to ground which maintains this relay operated until the battery 251 is fully charged or until the charging is stopped manually. The energization of relay 255 completes an operating circuit for the carbon contact relay

254, which circuit is closed from grounded battery, winding of this relay, upper front contact and armature of relay 255, upper back contact and armature of relay 257 to ground. Relay 254 when thus energized

25 closes contacts 258 and 259 thereby completing a charging circuit from the source of alternating current over conductor 261, contacts 259 and 258, through the rectifier 250, ammeter 262 to one side of battery 251 and

from the grounded side of battery, through the rectifier 250, conductor 263 to the source of alternating current. Under the control of this circuit battery 251 is charged until a predetermined voltage is reached, where-

upon the voltmeter relay closes its contacts 253. This completes a circuit from ground, through contacts 253, overcharge key contacts 270, winding of relay 257 to grounded battery. Relay 257 is operated in this cir-

257 cuit and opens the holding circuit previously mentioned for the relay 255. Relay 255 then deenergizes and opens the actuating circuit of the carbon contact relay 254 which

254 in turn deenergizes to open the power circuit. In the event that it is desired to charge battery 251 before the voltage has

reached the predetermined minimum a start key 265 is depressed manually to close a circuit for the relay 255 which functions

255 as already described to start charging the battery 251. In the event that it is desired to stop the charging independently of the automatic control, the star key and the over-

charge key are both depressed to complete an actuating circuit for the relay 257 through contacts 267 of the over-charge key and contacts 266 and 268 of the start key to ground. Relay 257 is thus ener-

257 gized and opens a locking circuit of relay 257 to stop the charging of the battery as

257 has been described.

What is claimed is:—

1. In an automatic telephone system, a plurality of telephone lines, one or more signals, actuating means for operating said signals according to code, means including one or more non-numerical switches to connect a telephone line to said actuating means to directively operate the same, a second line, and means controlled over said second

- line for disabling said actuating means and for connecting said first and second lines through non-numerical switches only.
2. In an automatic telephone system, a plurality of telephone lines, a plurality of bridge circuits, a plurality of number-storing devices, means including primary and secondary non-numerical switches operating responsive to the initiation of a call on a telephone line for connecting said line to a bridge circuit, means for connecting an idle number storing device to the selected bridge circuit, a code signaling device, means controlled over the two sides in series of the calling line for selectively operating the connected number storing device, a switching mechanism for connecting the code signaling device to the calling line under the control of the operated number-storing device, means controlled over the calling line for selectively operating said code signaling device, and means controlled from any of said other lines for disabling said code-signaling device and for connecting said last mentioned line to said calling telephone line.
3. In an automatic telephone system, a plurality of telephone lines, a plurality of link circuits, a code signaling device, means including a calling line and a selected link circuit for directly operating said code signaling device, means including a second telephone line and a second link circuit for disabling said code signaling device, and means including a non-numerical switch for interconnecting said first and second mentioned link circuits.
4. In an automatic telephone system, a plurality of telephone lines, a plurality of link circuits, means for interconnecting a calling line and a link circuit, code signaling means, a code signaling switch, means including a calling line and a selected link circuit for directly operating said code signaling switch, said last mentioned means being arranged for continuing the operation of said switch at will to actuate the code signaling means in accordance with the setting of said code signaling switch.
5. In an automatic telephone system, a plurality of telephone lines, a plurality of link circuits, non-numerical switches for interconnecting said lines when calling with idle link circuits, one or more code signals, a code selector for variably operating said code signals, means including a calling telephone line and a selected link circuit for selectively operating said code selector, a plurality of relays arranged to be selectively operated under the control of said code selector, means including said code selector and said actuated relays for selectively operating said code signals, and means controlled over a second line for disabling said code selector.
6. In an automatic telephone system, a plurality of telephone lines each provided with a calling dial, a plurality of link circuits, non-numerical switches for interconnecting said lines when calling with idle link circuits, one or more code signals, a code selector for variably operating said signals, means including a calling telephone line and a selected link circuit for selectively operating said code selector, a plurality of relays arranged to be selectively operated under the control of said code selector and means including said code selector and said actuated relays for selectively operating said code signals, means including the dial of the calling line for repeating the operation of said code selector, means controlled over a second line for disabling said code selector, and means including non-numerical switches only for interconnecting said second line and said calling line.
7. In an automatic telephone system, an operator's position, a plurality of telephone lines, each provided with an impulse sending device, a plurality of link circuits, non-numerical switches, means including non-numerical switches for connecting said telephone lines when calling to idle link circuits, a plurality of register senders, means effective on the seizure of a link circuit for associating an idle register sender therewith, means including said impulse sender and the calling telephone line for selectively operating said register sender to select the operator's position, means responsive to such selection to extend the calling line and selected link to the operator's position through non-numerical switches exclusively, and means at said operator's position for extending the calling telephone line and its selected link circuit to a wanted telephone line.
8. In a telephone system, a plurality of telephone lines, a plurality of link circuits, means including non-numerical switches for interconnecting a telephone line and a link circuit, an operator's position, a plurality of operator's trunk circuits at said operator's position, means including non-numerical switches for connecting operator's trunk circuits to link circuits, a plurality of register senders, means for associating an idle register sender with a link circuit, a dial impulse sending device at said operator's position common to said operator's trunk circuits, a common dial key at said operator's position for connecting the dial impulse sending device to a selected trunk circuit, said impulse sending device being effective to selectively actuate said register sender, means responsive to the setting of said register sender for extending a wanted telephone line through a selected link circuit to the operator's trunk circuit, and means for causing said impulse sending device to complete its operation of sending a

series of impulses over the selected trunk irrespective of whether or not said dial key is released before said impulse sending device has completed its operation.

5 9. In a telephone system, an operator's position, a plurality of trunk circuits terminating at said position, a plurality of telephone lines, a rotary impulse sending dial common to said trunk circuits, means including a common key for connecting said impulse sending dial to any selected trunk, means responsive to the operation of said impulse sending dial for extending a selected operator's trunk to a wanted telephone line, and means for causing said impulse sending dial to complete its operation of sending a series of impulses over the selected trunk irrespective of whether said dial key is released before its operation is completed.

10 10. In a telephone system, a plurality of telephone lines, an operator's position, a plurality of operator's trunks terminating thereon, an impulse sending dial at said operator's position, a common dial key at said position, a dial relay functioning to connect said impulse sending dial to a selected trunk circuit, a second relay arranged to be operated during the time that said impulse dial is sending impulses, a plurality of operating circuits for said dial relay, one of said circuits being completed through normally open contacts of said dial key and a second circuit being completed through normally closed contacts of said dial key and contacts of said second mentioned relay, and devices operated over said trunk circuit in response to said impulses to interconnect the operator's trunk circuit and a wanted telephone line.

15 11. In a telephone system, an operator's position, a plurality of telephone lines, a plurality of operator's trunk circuits, link circuits, non-numerical switches, a register sender, means actuated in accordance with the designation of a wanted telephone line for selectively operating said register sender, means responsive to the adjustment of said register sender for extending an operator's trunk circuit to a called telephone line through link circuits and non-numerical switches only, and means for manually extending the operator's position to a calling telephone line.

20 12. In a telephone system, a plurality of telephone lines, a plurality of progressively movable non-numerical switches having brushes, a plurality of telephone lines terminating in the movable brushes of each non-numerical switch, fixed contacts for

said switches for engagement by said brushes, trunk circuit terminating in said fixed contacts, an operator's position, means effective after the initiation of a call on one of said telephone lines for extending the same through the brushes of a non-numerical switch over a trunk circuit to said operator's position.

25 13. In an automatic telephone system, a plurality of telephone lines, a plurality of line switches, each having brushes and fixed contacts, a plurality of said telephone lines terminating in the movable brushes of each line switch, primary trunks terminating at one end in said fixed contacts, secondary line switches each having brushes and fixed contacts, each primary trunk terminating at its other end in the movable brushes of a secondary line switch, link circuits terminating in the fixed contacts of said secondary line switches, an operator's position and means effective to interconnect a calling telephone line to said operator's position through primary and secondary line switches and a primary trunk and link circuit.

30 14. In an automatic telephone system, a plurality of telephone lines, an operator's position, means including switches of the non-numerical type only through which said telephone lines and said operator's position may be interconnected, a trunk to a distant office, manual means for connecting said operator's position to said trunk, intercepting means in said operator's position for rendering ineffective the connection of a calling telephone line to said trunk, and means associated with certain of said telephone lines for disabling said intercepting means.

35 15. In an automatic telephone system, a plurality of telephone lines, an operator's position with one or more jacks, an operator's trunk terminating in one of said jacks, means including switches of the non-numerical type only through which a calling telephone and said operator's trunk may be interconnected, an inter-office trunk terminating at said operator's position, means including a cord circuit provided with at least one plug for interconnecting said inter-office trunk and the jack connected to said operator's trunk, intercepting means at said operator's position including said jack for interrupting said operator's trunk, and means associated with certain of said telephone lines for rendering said intercepting means ineffective.

40 In witness whereof, I hereunto subscribe my name this 18th day of August A. D. 1922.

WINFRED T. POWELL.
